CLAIM

The ornamental design for a window security bar, as shown and described.

DESCRIPTION

FIG. 1 is a front, left, and top perspective view of window security bar, showing my new design;

FIG. 2 is a rear, left, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is an enlarged top plan view thereof;

FIG. 8 is an enlarged bottom plan view thereof;

FIG. 9 is a detailed view taken from the encircled portion labeled "9" in FIG. 1;

FIG. 10 is a detailed view taken from the encircled portion labeled "10" in FIG. 1;

FIG. 11 is a detailed view taken from the encircled portion labeled "11" in FIG. 3;

FIG. 12 is a detailed view taken from the encircled portion labeled "12" in FIG. 3;

FIG. 13 is a detailed view taken from the encircled portion labeled "13" in FIG. 5; and,

FIG. 14 is a detailed view taken from the encircled portion labeled "14" in FIG. 5.

The short-dash and long-dash broken lines in FIGS. 1, 3, 5, and 9-14 denote the boundaries of the detail areas and form no part of the claimed design. The even broken lines depict portions of the window security bar and form no part of the claimed design.

1 Claim, 14 Drawing Sheets
